UNITED STATES PATENT OFFICE.

LEWIS R. WALLACE, OF WALTHAM, MASSACHUSETTS, ASSIGNOR TO NEVENS-WALLACE TRAIN CONTROL COMPANY, A CORPORATION OF MASSACHUSETTS.

TRAIN-CONTROL SYSTEM.

1,305,757.

Specification of Letters Patent. Patented June 3, 1919.

Application filed July 15, 1912. Serial No. 709,346.

To all whom it may concern:

Be it known that I, LEWIS R. WALLACE, a citizen of the United States, residing at Waltham, county of Middlesex, Commonwealth of Massachusetts, have invented certain new and useful Improvements in Train-Control Systems, of which the following is a specification.

This invention relates to the positive control of railroad trains and the like, for the purpose of preventing the neglect or disobedience of the usual signals employed in such systems. The invention is particularly adapted to be used in block systems where trains are to be kept absolutely within certain block limits.

My invention is capable of independent use and also as an auxiliary to the usual block system, or indeed by a simple matter of wiring it may be embodied as part thereof. By it a train proceeding either intentionally or unintentionally past a signal will be under absolute control.

In the form of my invention, to which I shall especially refer herein, the train controlling means is a tripper adapted to be thrown across the tread of the rail just after a wheel has passed in order to engage and actuate a tripping device which operates the braking system of the train.

In the specification which follows, I shall make particular reference to a form of stopping mechanism which I have found well adapted for practical use, and which is capable of effective operation under the ordinary circuit conditions of railroad signals.

This device together with the connections shown will serve as an illustrative embodiment of the principles involved in my invention. Throughout specification and drawings like reference numerals are employed to indicate corresponding parts, and in the drawings:

Figure 1 is a plan view of a section of track equipped with my stopping device and with the connections indicated for the operation thereof;

Fig. 2 is a transverse section through my stopping device showing the parts in non-interfering position to indicate that there is a clear track ahead;

Fig. 3 is a similar view showing the parts

of my stopping device, showing the tripper in closed position over the rail, which position it would occupy immediately after the 55 passage of a wheel,

Fig. 4 is a longitudinal section through my stopping device showing the tread engaging plate,

Fig. 5 is an enlarged view of my electrical 60 locking and unlocking mechanism, and

Fig. 6 is a detail view particularly illustrating the depressible tread engaging plate.

For the purposes of explanation I have illustrated four sections of track, A, B, C, 65 and D, (see Fig. 1). These are insulated from each other at a, b and c. The sections are, on account of the limited space, shown very short, but it will be understood that each one is intended to represent a block of 70 more than a train length in extent.

Within the section B, and at a suitable distance from the beginning of section C, I mount my tripping mechanism which may be supported on two ties, as indicated at T, 75 7. The tripping device comprises a tripping finger 1 pivoted at 2 in suitable ears 3 on a rail plate 4. The tail of the lever 1 is pivoted at 5 on a cross rod 6 running transversely of the track and guided by a plate 80 7. Between the flange of the plate 7 and the collar 8 on the rod 6 is coiled a spring 9 which tends to thrust the finger 1 into its tripping position in which it overlies the rail.

Mounted adjacent the rail opposite the rail near which the finger 1 is located is a depressible device, the effective position of which is controlled by the condition of the block C. This structure consists of a depressible plate 10 positioned parallel with and adjacent to the rail on the outside thereof so as to be within the path of the overhanging tread of the car wheel in passing. The plate 10 is provided at each end with 95 arms 10² which are connected to a bar 10¹ positioned substantially parallel to the plate 10 and provided with studs 11 at each end which are received in bearings 12 on the ties T. Depending from the bar 10¹ is an arm 100 13, the lower end of which is pivoted at 14 in the bifurcated end of the rod 6. When the plate 10 is positioned in interfering relation to the train wheels, a depression of

85

90

95

100

said plate will through the connections 10² and 10¹, 13 and 14 give a transverse movement to the rod 6 thereby moving the finger 1 away from the opposite rail and out of 5 tripping position just before it would be struck.

The finger 1 is thrown across the rail just after each wheel passes. The corresponding wheel on the opposite side of the track begins to depress the plate 10 and thus withdraws the finger 1 just before the finger 1 would be struck. The action of the device is therefore to pull the finger 1 off of the track just before the wheel hits it and drop 15 it back on to the rail just after the wheel has passed. As a train therefore moving in the direction of the arrow passes over the plate 10 on section B it will depress that plate and throw the tripper 1 unless the 20 plate 10 be held in depressed position. As it is not desired to have the tripper effective unless there is a train already on block section C, I therefore provide a locking mechanism for holding the plate 10 in depressed 25 position and the tripping finger 1 away from its engaging position on the track.

This locking mechanism comprises a pair of magnets 20 with an armature pivoted at 22 and working against a stop 23. A spring 30 24 tends to hold the armature 21 away from the magnets 20 in which position the end of the armature 21 clears the notched end of the lever 25, permitting it to drop as shown in Fig. 3, thus releasing the end of the lever 35 26 pivoted at 27 which is normally held within a recess 28 formed between the arm 25 and a spur 29.

In the position shown in Fig. 2, the lever 40 26 has an end resting within the recess 28 and is held in this position by the arm or lever 25. This lever 25 is held by the armature 21 which supports it and prevents it from dropping as long as the armature is held against the magnets 20 by the closed 45 circuit. When the circuit is broken, however, the armature 21 is thrown out by the spring 24 and the lever 25 dropped, thus permitting the drop of the end of the lever 26 and allowing the rise of the plate 10 under the action of the spring 9.

The lever 26 beyond the pivot 27 is pivoted at 51 to a link 52 fastened at 53 to the arm 10² of the plate 10, see Fig. 6. The movement of the plate 10 is therefore transmitted to the lever 26.

Each time the plate 10 is depressed the end of the lever 26 passing the spur 29 lodges within the recess 28 and raising the lever 25 makes it possible for the armature 60 21 to be drawn under it and supported if the circuit is closed at the time.

It will thus be seen that as long as the circuit is closed the plate 10 will remain locked in depressed or non-operative position, or if it is not already locked at the time

the circuit is closed it will become locked as soon as the plate 10 is depressed by a car wheel.

As indicating a simple circuit for operating this lock, I have shown in Fig. 1 wires 70 30 and 31 leading from the winding of the magnets 20 to each of the rails in the section C. Leading to these same rails also are electrical connections 32 and 33 from the battery 34. The section C is therefore a 75 complete circuit until short circuited by the wheels of the train which is run over it.

As a train approaches section C, if the track is clear, the circuit in section C will be complete. If the stopping device is in the 80 position shown in Fig. 1 nothing will happen and the train will simply pass by into section C. If it should happen that the tripping device has been left in the position shown in Fig. 3, prior to the completing of 85 the circuit of section C and that circuit had thereafter become completed so that the block C was in reality clear, then the first wheel which passes over the plate 10 would restore the tripping device to the position shown in Fig. 1 so that no actual tripping 90 would take place but the train would be permitted to pass into the block C.

As soon, however, as the train has passed insulation b and entered block C, the current from the battery 34 in that block is short circuited across the track C by the wheels and the armature 21 released so that the spring 24 throws it out from its supporting position, allowing the lever 25 to 100 drop, releasing the lever 26 and permitting the plate 10 to be raised by the spring 9 to its contacting position.

As long as there is a train on the block C, any train approaching the tripping device 105 will find the plate 10 in engaging position so that as soon as a wheel comes in contact with the plate 10 the tripping finger 1 will be snapped down behind the wheel to engage the tripping mechanism for setting 110 the brakes. This tripping mechanism for setting the brakes and stopping the train may be of any desired construction, as that set forth in the application of Herbert R. Nevens, filed June 19, 1911, serially numbered 115 634,010. It will thus be seen that my device constitutes a positive stop for a train approaching a block already occupied or in which the circuit is broken by any accident to the rails, or if connected with the ordinary 120 signaling circuit it will be effective if the signaling circuit is out of order.

While I have shown and particularly described the features of my present invention as embodied in a positive control system, yet it will be readily understood that they may be utilized in a system in which signals for control or the like are to be transmitted.

Various modifications may obviously be 130

- made in the details and construction and operation of my device, all without departing from the spirit of my invention if within the limits of the appended claims.
5. What I, therefore, claim and desire to secure by Letters Patent is:
1. A device of the class described comprising a movable plate mounted adjacent to one rail of a trackway within the influence of the wheels of a passing train, a movable finger positioned over the opposite rail of said trackway, and means effective upon the engagement of said plate by said wheels to automatically remove said finger from 15 over the rail.
  2. A device of the class described comprising a movable arm positioned adjacent to one rail of a trackway within the influence of the wheels of a passing train, a movable finger positioned over the opposite rail of said trackway, means effective upon the engagement of said plate by said wheels to automatically remove said finger from such operating position, and means 25 for locking said arm and said finger away from their operative positions.
  3. A device of the class described comprising a pivoted plate positioned adjacent to one rail of a trackway within the influence of the wheels of a passing train, a movable finger pivoted for movement over the opposite rail of said trackway for engagement with the braking system of a train, a link connecting said plate and said finger to move the latter from across the rail upon the engagement of said plate by said wheels and a resilient member effective to return said finger to operative position across said rail upon the passage of a wheel.
  4. A device of the class described comprising a pivoted plate positioned adjacent to one rail of a trackway within the influence of the wheels of a passing train, a movable finger pivoted for movement over the opposite rail of said trackway for engagement with the braking system of a train, a link connecting said plate and said finger to move the latter from across the rail upon the engagement of said plate by said wheels and a resilient member effective to return said finger to operative position across said rail upon the passage of a wheel, and means for locking said plate and said finger away from their operative positions.
  5. A device of the class described comprising a movable plate operatively mounted adjacent to one rail of a trackway within the influence of the wheels of a passing train, a movable finger positioned over the opposite rail of said trackway for operatively influencing the brake system of a train moving along said trackway, means effective upon the engagement of said plate by said wheels to automatically remove said finger from such operating position and automatic means for returning said finger when said arm is released from the influence of said wheels.
  6. A device of the class described comprising a movable plate positioned adjacent to one rail of a trackway within the influence of the wheels of a passing train, a movable finger positioned over the opposite rail of said trackway and effectively disposed when in operating position in the path of a brake setting mechanism carried by said passing train to actuate said mechanism, an operating connection between said plate and said finger, and an operating system in control of the movement of said plate and finger for operative and inoperative positions. 70
  7. A device of the class described comprising a movable plate operatively mounted adjacent to one rail of a trackway within the influence of the wheels of a passing train, a movable finger positioned over the opposite rail of said trackway for operatively influencing the brake system of a train moving along said trackway, and means effective upon the engagement of said plate by said wheels to automatically remove said finger from such operating position. 75
  8. In combination with a trackway an actuating device for establishing a communication with a train moving thereon and comprising a tripper movably mounted relative to one rail of said trackway and normally disposed in the path of the wheels of a train on said trackway, an operating mechanism operatively associated with the opposite rail of said trackway, connecting means between said operating mechanism and said tripper and effective to withdraw said tripper from the trackway. 80
  9. A device of the class described comprising a moving member normally positioned over a track, a wheel engaging member, and an operative connection between said moving member and said wheel engaging member for removing it from the track as a wheel passes and returning it immediately upon the passage of the wheel. 85
  10. In combination with a track an actuating arm for an air brake system said arm being movably mounted in relation to said track and normally lying in the path of the wheels of a train in passing thereon, and operating means disposed in the path of such wheels and operatively connected to said arm to remove the same from the path of the wheel while the wheel is passing. 90
  11. A signaling device of the class described comprising a movable arm positioned adjacent to one rail of a trackway and normally in the path of the wheels upon said rail, an operating device operatively associated with the opposite rail and adapted to be effectively engaged by wheels passing on said opposite rail, and a connection 95
  12. A device of the class described comprising a movable plate positioned adjacent to one rail of a trackway within the influence of the wheels of a passing train, a movable finger positioned over the opposite rail of said trackway for operatively influencing the brake system of a train moving along said trackway, means effective upon the engagement of said plate by said wheels to automatically remove said finger from such operating position and automatic means for returning said finger when said arm is released from the influence of said wheels. 100
  13. A device of the class described comprising a movable plate positioned adjacent to one rail of a trackway within the influence of the wheels of a passing train, a movable finger positioned over the opposite rail of said trackway and effectively disposed when in operating position in the path of a brake setting mechanism carried by said passing train to actuate said mechanism, an operating connection between said plate and said finger, and an operating system in control of the movement of said plate and finger for operative and inoperative positions. 105
  14. A device of the class described comprising a movable plate positioned adjacent to one rail of a trackway within the influence of the wheels of a passing train, a movable finger positioned over the opposite rail of said trackway for operatively influencing the brake system of a train moving along said trackway, and means effective upon the engagement of said plate by said wheels to automatically remove said finger from such operating position. 110
  15. A device of the class described comprising a movable plate positioned adjacent to one rail of a trackway within the influence of the wheels of a passing train, a movable finger positioned over the opposite rail of said trackway and effectively disposed when in operating position in the path of a brake setting mechanism carried by said passing train to actuate said mechanism, an operating connection between said plate and said finger, and an operating system in control of the movement of said plate and finger for operative and inoperative positions. 115
  16. A device of the class described comprising a movable plate positioned adjacent to one rail of a trackway within the influence of the wheels of a passing train, a movable finger positioned over the opposite rail of said trackway for operatively influencing the brake system of a train moving along said trackway, and means effective upon the engagement of said plate by said wheels to automatically remove said finger from such operating position and automatic means for returning said finger when said arm is released from the influence of said wheels. 120
  17. A device of the class described comprising a movable plate positioned adjacent to one rail of a trackway within the influence of the wheels of a passing train, a movable finger positioned over the opposite rail of said trackway and effectively disposed when in operating position in the path of a brake setting mechanism carried by said passing train to actuate said mechanism, an operating connection between said plate and said finger, and an operating system in control of the movement of said plate and finger for operative and inoperative positions. 125
  18. A device of the class described comprising a movable plate positioned adjacent to one rail of a trackway within the influence of the wheels of a passing train, a movable finger positioned over the opposite rail of said trackway for operatively influencing the brake system of a train moving along said trackway, and means effective upon the engagement of said plate by said wheels to automatically remove said finger from such operating position and automatic means for returning said finger when said arm is released from the influence of said wheels. 130

between said operating means and said arm for removing said arm from the path of a wheel during the passage of the wheel and to return the arm to normal position 5 when the wheel has passed.

12. In a signaling device of the class described in combination with an insulated section of track a movable tripping member associated with one rail of said track and 10 adapted to lie in the path of the wheel thereon or to be removed from said position, a wheel contacting member on the opposite rail and operatively connected to said tripping member to remove said member from the path of the wheel when engaged with the opposite wheel, an electrically controlled catch for holding said tripping member in withdrawn position, including a circuit connected with another section of said track.

13. In a device of the class described a 15 compressible plate, means for mounting said plate adjacent to a rail, a laterally movable finger, means for mounting said finger adjacent to said other rail, means for normally holding said finger over said rail, a connection between said plate and said finger for moving said finger upon the operation of said plate, a locking connection, a locking device adapted to receive said locking 20 connection to hold said plate depressed, including a normally effective electrical connection, and means for unlocking said locking connection when the circuit of said electrical connection is broken.

14. In a device of the class described, a compressible plate adjacent to one rail, a finger adjacent to the other rail and laterally movable relative thereto, a connection between said plate and said finger for moving 25 said finger upon the operation of said plate, a lever pivoted between its ends and connected to said plate at one end, a pivoted notched locking piece adapted to receive the other end of said lever when held up to hold 30 said plate depressed, a pivoted armature having its free end movably mounted under said locking piece, a magnet for moving said armature under said locking piece, and a spring for throwing said armature out 35 from under said locking piece.

15. In combination with a trackway, an air brake actuating device movably mounted relative thereto and having an interfering position in the path of the wheels of a passing train and a non-interfering position out 40 of the path of the wheels, and an operating device disposed in the path of the wheels of said train and operatively connected to said actuating device to withdraw the actuating device during the passage of the 45 wheels and immediately restore it after such passage.

16. A device of the class described comprising a moving member normally positioned over a track, a wheel engaging mem-

ber, and an operative connection between said moving member and said wheel engaging member for removing it from the track as a wheel passes and returning it immediately upon the passage of the wheel, and means for locking said moving member and said wheel engaging member in said removed position.

17. In a device of the class described, the combination of an insulated section of 75 track, a movable member normally positioned over one rail of said track, a wheel contacting member, and an operative connection between said movable member and said wheel contacting member, an electrically controlled catch for holding said movable member in withdrawn position, including a circuit operably associated with another section of said track.

18. In a device of the class described, in 80 connection with an insulated section of track, a moving member normally positioned over an approaching section of the track, a wheel engaging member adjacent to the moving member, an operative connection between said moving member and said wheel engaging member for removing the moving member from the track as a wheel passes and returning it immediately upon the 85 passage of the wheel, an electrically controlled locking device for holding said moving member in removed position, and a circuit including said insulated track section and said locking device.

19. In automatic train stop apparatus, a 90 control mechanism for a brake system relief member actuator located along the trackway and adapted to be moved into and out of actuating relation to the relief member, comprising a controlling device disposed adjacent the trackway and adapted to be actuated by a train, and having an interfering and a non-interfering position relative thereto, a lock normally holding 95 said control device in its non-interfering position, a release for said lock allowing said control device to move to its interfering position, and an operative connection between said control device and said actuator effective to maintain said actuator in non-actuating position when said control device is locked and moving said actuator to its actuating position when the control device is released.

20. In automatic train stop apparatus, a 100 control mechanism for a brake system relief member actuator located along the trackway and adapted to be moved into and out of actuating relation to the relief member, comprising a controlling device disposed adjacent a rail of the trackway and adapted to be actuated by a wheel of the train, and having an interfering and a non-interfering position relative thereto, an 105 electromagnetic lock normally holding said 110

control device in its non-interfering position, a release for said lock allowing said control device to move to its interfering position, and an operative connection between said control device and said actuator effective to maintain said actuator in its non-actuating position when said control device is locked and moving said actuator to its actuating position when the control device is released.

21. In automatic train stop apparatus, a control mechanism for a brake system relief member actuator located along the trackway and adapted to be moved into and out of actuating relation to the relief member, comprising a track trip having an actuating and a non-actuating relation to a train-carried part, an oscillatable support for said track trip, an automatic locking mechanism normally maintaining said track trip in non-actuating position relative to said train-carried part, and a motion transmitting connection from said track trip to said relief member actuator adapted to move said actuator to actuating position relative to the relief member upon movement of the track trip to interfering position relative to said trip-actuating device.

22. In automatic train stop apparatus, a control for a brake system relief member actuator located along the trackway and having a variable position relative to the path of the relief member, comprising a train-operated controlling element for the actuator disposed at the trackway, and a motion transmitting connection between said control element and actuator and actuated by the operation of said control element to remove said actuator from the path of said relief member.

23. In automatic train stop apparatus, a control mechanism for a brake system relief member actuator located at the trackway and having a variable position relative to the path of the relief member, comprising a track trip adapted to be actuated by a train wheel, and a motion transmitting connection from said trip to said actuator for removing said actuator from the path of said relief member upon actuation of the track trip by a train wheel.

24. In automatic train stop apparatus, a control mechanism for a brake system relief actuator disposed adjacent one rail of the trackway and adapted to be moved into and out of actuating relation to the relief member, comprising a control device for said relief member actuator disposed adjacent the other rail of the trackway and having an actuating and a non-actuating relation to a train-carried part, a releasable lock for said control device, and an operative connection between said control device and said relief member actuator including a spring normally maintaining said relief member actuator in non-actuating position relative to said relief member, said spring being overcome by the release of said lock and the movement of said control device to its actuatable position to allow the relief member actuator to move to its actuating position, and said control device when actuated by the train carried actuating part moving said relief member actuator to its non-interfering position.

In testimony whereof I affix my signature in presence of two witnesses.

LEWIS R. WALLACE.
